UNITED STATES PATENT OFFICE

2,344,556

DISPENSER.

Robert E. Manley, York, Pa.

Application October 10, 1940, Serial No. 360,668

4 Claims. (Cl. 225—22)

This invention relates to dispensing devices and has for its principal object the provision of a simple and efficient dispenser for conveniently holding a bottle of charged water so as to discharge a part of its contents into a glass to mix same with other liquids.

A further object of the present invention consists in providing an assembly for use in a private or public bar which will conveniently receive the usual quart capped bottle of sparkling water and discharge its contents into a mixed drink without the necessity for the use of a spoon to stir the contents of the highball or other beverage. In the past seltzer and soda water were readily available in heavy metal topped syphon bottles but the use of this type container has more recently met with disfavor, partly because of the weight of the bottle and partly because of the sharply increased cost of the discharge cap and valve commonly made of block tin.

At the present time, therefore, most bars keep on hand four or five bottles of the different brands of sparkling water, mixers, ginger ale, etc., and after using the bottle it is usual to cork it with a rubber stopper to preserve the gas. The ginger ale or other mixer is poured directly into the serving glasses from the bottle and since ice is frequently used it is necessary for the server to stir the contents beneath the ice with a long-handled spoon.

With the use of my device a mixed drink such as a highball can more quickly and conveniently be served for the gooseneck of my invention has a curvature such that its tip may be inserted in the serving glass between the ice and the whiskey so that the force of the water under the carbonated pressure thoroughly mixes the whiskey with the water and makes it unnecessary to stir with the usual spoon.

My device is also very convenient for service in the home, particularly since any of the usual charged waters can be purchased in quart bottles at almost any grocery store whereas it is almost impossible to purchase charged water in syphon caps in a grocery store of any kind, even the larger stores.

A further object of my invention lies in the provision of a valve specifically adapted to discharge fluid from an inverted charged bottle, the pressure of the carbonated water being used to hold the valve against its seat, aiding the usual spring which is manually compressed when it is desired to dispense the beverage.

In the drawing:

Figure 1 is a side elevation of a device embodying my invention, partly in section.

Figure 2 is a section through the valve at right angles to the view of Figure 1.

Figures 3 and 4 show modified forms of support.

Figure 5 shows my device supported on a wall.

In the preferred form of my device the assembly consists of a bottle 10, a frame 11, a valve 12, a clamp 14 and a support 15. The frame includes a base 16 preferably of ring shape adapted to support an upright bottle on a table or other flat object. The base 16 is provided with a plurality of bosses 17 to receive standards 18 permanently secured to the bosses as by the pins 19. The base 16 also has a lateral projection or ear 19 pierced for a purpose later to be described. The free end of the standards 18 are secured in a cross bar 20 as by pins 21 and the cross bar 20 carries a projection 23 in alignment with the ear 19 and cooperating with it to support the frame as later to be described.

25 In a central boss 25 on the cross bar 20 is mounted a threaded stem 26 to which is secured a hand wheel 27 and a head 28, the latter being a clamping piece to bind the valve 12 and bottle 10 in the frame so that these members may conveniently be handled as a single unit.

30 Referring particularly to Figure 2, the valve 12 consists of a body 30 having a central bore in which slides a stem or plunger 31 having a reduced portion 32 on the end of which is mounted the valve seat 33 which carries a rubber disk to close the bore in the body 30. A nut 35 closes the enlarged chamber 36 which houses the spring 37 which urges the valve into closed position. In the recess 38 is mounted a rubber washer 39 engaging the open mouth of the bottle. A passage-40 way 40 leads from the recess 38 to the chamber 36, thus causing the pressure in the bottle to operate with the spring to keep the valve closed.

45 A strut 42 serves to support the pivoted handle 43 by means of which the server presses the plunger or valve stem 31 against the spring 37 and releases the contents of the bottle through a lateral opening indicated by dotted lines 44, this leading to the gooseneck 45 which when the unit is assembled is in inverted or serving position, directed outwardly and downwardly for the convenient mixing of the drink to be served.

50 The unit assembly may be supported in any desired manner, my preference being to have a standard 50 having a ring shaped bottom 51 and

carrying a relatively heavy post 53 having a screw or pin connection with the standard 50 of the support 15. The lower portion of the support 15 is slotted as at 54 to receive the round pin 23 while the upper free end 55 of the post 53 extends through the opening in the ear 19 or if preferred, into a socket in the ear 19. In either case the unit may be lifted off of the post 53 as soon as the pin 23 is moved from the slot 54, there being a reasonable amount of play between the top of the post 53 and the opening or recess in the ear 19.

When the device is used on a boat I prefer to extend the pin 23 a trifle as illustrated at 56 and to form an opening in the extending end of 15 the pin so as to receive a cotter 57, this provision preventing the lurching of the boat from causing the unit to be detached from the support or stand 15. For use other than marine I prefer that the pin 23 shall only extend the thickness of the support 50.

In the modified form shown in Figure 3 the base of the support is a ring 60 which may be secured to a supporting surface as by the screws 61. At diametric portions of the ring 60 I provide hollow posts 62 and in this modification the cross piece 20a is pierced to receive the standards 18 which may be secured as by the pins 21 or by set screws 65, so that the standards 18 may project sufficiently far into the tubes 62 as to afford ample support for the unit. This type is particularly suitable for use on yachts or on other boats.

In Figure 4 I substitute for the pin 23 a fork 66 which may straddle the post 53a set into the standard 50a, the base 67 of which carries a clamp 68 of usual design so that the support may be clamped to a table top or other object. The top of the standard 50a supports the unit which is held at the top by the ear 19. Obviously if the hand wheel 27 of the clamp 14 were greatly increased in diameter, it alone could support the unit in the serving (inverted) position, and this simple form is sometimes preferred by users.

In Figure 5 I show the unit supported directly from a wall which carries a bracket 70 and a staple 71 for the forked type such as 66 or a recess 72 for receipt of the pin type as shown at 23. In this modified form the base 16a instead of being pierced as in the preferred form carries a socket 74 which receives the free end of the bracket 70 exactly as it receives the top of the post 53 while the form 66a engages the staple 71 driven in the wall at the proper distance below the bracket 70. In this modification the bottle has very slight movement as is the case in the preferred form.

When the preferred form has a fork such as 66 in place of the pin and this fork rests upon the standard 50a the bottle may swing completely around the axis of the post 53a which in some cases may be preferred. Obviously in this type two or more units containing two different bever-

ages may be supported from the same post, 53a.

What I claim is:

1. In combination, a base for supporting an erect bottle on a substantially horizontal surface such as a table top, vertical members extending from the base on opposite sides of the bottle, an assembly including a manually operated clamp connecting the tops of the vertical members to form a frame whereby a bottle having a valve loosely seated on its open top may be clamped in the frame to form a unit structure for convenient handling, and means independent of said unit structure for supporting the unit in inverted position.

2. In combination, a base having means for supporting an erect uncapped bottle on a horizontal surface such as a table top, vertical members extending from the base on opposite sides of the bottle, an assembly including a cross member connecting the tops of the vertical members to form a frame, and a manually operated clamping screw whereby a bottle having a valve loosely seated on its open top may be clamped in the frame to form a unit structure for convenient handling, a supporting structure and means on said base and means on said cross member cooperating to position the unit on said supporting structure by a spaced gravity connection with the unit inverted.

3. In a device for dispensing the contents of a bottle containing a carbonated beverage, a valve adapted to seat lightly upon the open top of a bottle of the type specified and having a spout, a seat for the bottom of the bottle, a cross member generally parallel to said seat, spaced means joining the cross member and the seat to form a frame, means having threaded engagement with said cross member to clamp the bottle and the valve in the frame to form a unit for handling, a vertical standard, an extension on the frame adapted to surround the upper end of the standard, and means carried by the frame for engaging the standard near the bottom thereof to transfer a major fraction of the weight of the unit to the lower part of the standard.

4. In a device for dispensing the contents of a bottle containing a carbonated beverage, a valve adapted to seat lightly upon the open top of a bottle of the type specified and having a spout, a seat for the bottom of the bottle, a cross member generally parallel to said seat, spaced means joining the cross member and the seat to form a frame, means having threaded engagement with said cross member to clamp the bottle and the valve in the frame to form a unit for handling, an eye on said seat and projecting means on said cross member cooperating to position the unit on a supporting structure by a spaced gravity connection.

ROBERT E. MANLEY.
